UNITED STATES PATENT OFFICE.

FRANCOIS EDOUARD CARDON, OF NEW YORK, N. Y.

FINGER-RING CONSTRUCTION.

1,018,875.

Specification of Letters Patent.

Patented Feb. 27, 1912.

Application filed February 13, 1911. Serial No. 608,415.

To all whom it may concern:

Be it known that I, FRANCOIS EDOUARD CARDON, a citizen of the United States, and resident of the city of New York, county of 5 Queens, and State of New York, have invented certain new and useful Improvements in Finger-Ring Construction, of which the following is a specification.

This invention relates to a finger ring 10 construction.

Rings of this type are ordinarily constructed with a single band encircling the finger upon which band is mounted the long support or base forming the mounting for 15 the jewels. The demand in the trade for rings of this type is for as long a jewel mounting as is possible and the tendency has been to increase this until rings of this type have become unwieldy and do not present 20 an attracting appearance upon the hand, especially when the finger is bent.

The object of this invention is to provide a construction for a finger ring of this type which when placed upon the finger will be 25 flexible and yield to the bending or any motion thereof and thus present a neat and attractive appearance as well as allowing the finger to be freely and naturally bent.

In carrying out my invention I provide a 30 flexible or jointed support or mounting for the jewels, to which are attached two or more encircling bands for the finger.

In the drawings I have shown a finger ring 35 of this construction to illustrate the invention.

The particular design of the jewel support may be varied to suit the individual tastes of the user.

In the drawings, like parts in the several 40 views have been given the same reference numerals.

Figure 1 is an enlarged side elevation of a finger ring, embodying the invention. Fig. 2 is a sectional end view on the line 45 2-2 of Fig. 1. Fig. 3 is a plan view of Fig. 1. Fig. 4 is a view showing the ring in position upon the finger, which is slightly bent.

The jewel support in the construction, as 50 illustrated, is composed of three sections, 1, 2 and 3. Each of these sections is provided with a finger encircling band, such as 4, 5 and 6, respectively. It will be understood that any number of sections desired 55 may be provided to form the jewel support

as well as any number of finger encircling bands attached thereto.

Between the supporting sections 1 and 2 a double hinge 7 and 8 is provided, the curvature of the two hinged portions conforming to the shape of the finger bands. A single hinge joint 9 is also provided between the support sections 2 and 3. It will be understood that other hinge joints or other forms of flexible connections may be provided and the jewel support divided into a greater number of sections, if desired, in order to provide a more flexible construction.

These rings are, of course, made to fit 70 the individual finger of the user and it will be seen that when placed in position upon the finger the same may be freely bent and the flexible jointed sectional support will yield or bend to conform to the bending of 75 the finger, as shown in Fig. 4.

The ring is preferably constructed of platinum, which is a very hard metal which does not tarnish and which lends itself readily to the hinge construction. It will 80 be understood, however, that the invention is not limited to any particular material, as this is largely a matter of individual taste.

As many changes could be made in the above construction and many apparently 85 widely different embodiments of my invention be designed without departing from the scope of the appended claims, I intend that all matter contained in the above description or shown in the accompanying 90 drawings shall be interpreted as illustrative merely of an operative embodiment of my invention and not in a limiting sense.

What I claim is:

1. A finger ring comprising a plurality 95 of finger encircling bands attached to a plurality of abutting jewel supporting members.

2. A finger ring comprising a plurality of finger encircling bands attached to a jewel 100 support composed of a plurality of elongated sections, said sections projecting transversely on each side of said bands and the adjacent ends of said projections being hingedly connected together.

3. A finger ring comprising a plurality 105 of finger encircling bands attached to a jewel support composed of a plurality of sections, and connecting means for said sections permitting relative angular tilting 110

- movement of said sections but preventing relative longitudinal movement thereof.
4. A finger ring having a plurality of finger encircling bands, a jewel support composed of a plurality of abutting sections attached to said bands, certain of said sections being connected together by a single hinge connection and certain others of said sections being connected by a double hinge connection.
5. A finger ring having a plurality of finger encircling bands, a jewel support composed of a plurality of sections attached to and projecting between said bands, a single hinged connection between certain of said sections, and a double hinge connection between two adjacent sections of said support having their axes at an angle to a horizontal plane to conform approximately to the circle of said bands.
10. 5. A finger ring having a plurality of finger encircling bands, a jewel support composed of a plurality of sections attached to and projecting between said bands, a single hinged connection between certain of said sections, and a double hinge connection between two adjacent sections of said support having their axes at an angle to a horizontal plane to conform approximately to the circle of said bands.
15. 6. A finger ring having a plurality of finger encircling bands, a jewel support composed of a plurality of elongated sections secured to said bands, and a double

hinge connection between two adjacent sections of said support, the axes of said hinges extending in a converging direction conforming to the circle of said bands.

7. A finger ring comprising a plurality of bands, jewel supporting sections projecting beyond the edges of each band, the adjacent edges of said jewel supports abutting each other to form a continuous jewel supporting surface, and hinges connecting said supports.

8. A finger ring comprising a plurality of bands, jewel supporting sections supported by said bands, the adjacent edges of said sections having interfitting parts, and hinges connecting said supports together.

Signed at New York city, in the county and State of New York, this 30th day of January, 1911.

FRANCOIS EDOUARD CARDON.
